United States Patent Office.

ANDREW JACKSON ROBERTS, OF BOSTON, MASSACHUSETTS.

Letters Patent No. 95,935, dated October 19, 1869.

IMPROVED MACHINE FOR MAKING HORSESHOES.

The Schedule referred to in these Letters Patent and making part of the same.

To all to whom these presents shall come:

Be it known that I, ANDREW JACKSON ROBERTS, of Boston, in the county of Suffolk, and Commonwealth of Massachusetts, have made a new and useful invention of an Improved Machine for Making Horseshoes; and do hereby declare the following to be a full, clear, and exact description thereof, due reference being had to the accompanying drawings, making part of this specification, and in which—

Figures 1 and 2 are opposite side elevations,

Figure 3, a plan,

Figures 4 and 5, vertical and transverse sections, and

Figure 6, a front end elevation of a machine containing my invention,

Figure 7 being a vertical central and longitudinal section of the same.

This machine, in its general construction, may be said to contain three distinctive devices, one for bending or giving the general yoke-shape of the shoe, one for indenting, or partially or wholly forming the nail-holes in the shoe, and incidentally giving a peculiar finish or angle to the faces thereof, and thirdly, a device for bending the heels of the shoe, or forming "calks" thereon, as it is termed, the whole being combined as hereinafter explained.

Incidental features of the invention consist in a device for feeding the material or blank iron into the machine, and for cutting the same into the requisite lengths, and for expelling the matured shoe from the machine.

The device for performing the operation of bending the shoe into its general shape, consists of two wings, hinged vertically to the main frame or bed of the machine, in such manner as to be capable of swinging lateral movements, such wings being provided at top with twin matrix-plates or formers, which operate in connection with an intermittent sliding die or mould-block, as hereinafter explained, the opening and closing movements of the wings being effected by two toggle-joints, of equal length and power, one of which is actuated by a crank-pin affixed to a revolving bevelled-gear wheel, applied centrally to the frame of the machine, and in rear of the wings before mentioned, the vertical reciprocating movements of the die or forming-block into and out of the plane of movement of the matrix-plates being effected by a lever, fulcrumed to the bed of the machine, and below the wings before mentioned, the forward and shorter arm of such lever being pivoted to the lower end of the die-block or its carrier, while the rear arm of such lever is extended into and is actuated by an irregular or cam-groove, formed within or upon a disk fixed to or making part of and revolving in unison with the gear-wheel before mentioned.

The device for punching the depressions or holes for the nails in the shoe consists of a series of punches, affixed to the lower end of a bar sliding vertically within the forward part of the frame of the machine, such bar and punches being disposed concentrically within the path of movement of the forming-plates or "formers," and operating in connection with the mould-block, before described, in such manner as to descend and punch the shoe after being formed about such mould, and while being held in position by the "formers," the movement of the punch-bar or carrier being effected by two horizontal levers, fulcrumed to opposite sides of the machine, and actuated by toggle-joints, pivoted to their rear ends, the longest arms of these toggle-joints in turn being operated (through the medium of a yoke or connecting-rod) by a compound cam, affixed to an upright pendent shaft carried by and revolving with a bevelled gear disposed immediately over the gear before mentioned as driving the toggle-joints which actuate the formers, the two gears being connected by an intermediate bevelled pinion, and the whole operating as hereinafter explained.

The device for bending the calks upon the heels of the shoe consists, first, of a yielding anvil or plate, having an extension upon its front part, and interposed between the lower end of the punch-bar and the mould-block, and through which the punches pass, as also in two movable abutments, for tapering the calks, affixed to or making part of the lower end of a carrier, sliding within the punch-bar before mentioned, and in an additional sliding bar or carriage, disposed below, and in alignment with the abutment before mentioned, the upper end of this last-mentioned bar being grooved, and embracing opposite sides of the extension of the anvil before alluded to, and operated in connection with the abutments and anvil, in such manner as to give an upward bend to the heels of the shoe, substantially as hereinafter explained, the anvil also serving the purpose of retaining the shoe in place about the mould-block while the punches are being drawn out of it, as well as to serve (by covering the shoe) as a means of maintaining the horizontal adjustment of the shoe while being bent.

The bar which carries the abutment is operated by the same levers which operate the punch-bar, while the necessary reciprocating vertical movements of the last-mentioned bar are effected by a lever pivoted to its lower extremity, and disposed alongside of, and of equal length with the lever before mentioned as actuating the mould-block, and upon the same fulcrum, the rear arm of the lever being actuated by an additional irregular groove, formed within the hub of the disk which actuates the mould-block lever, the whole being as hereinafter explained.

The anvil, before alluded to, is supported in position

by a long shank, from which it depends, this shank being disposed within a hole made vertically in the punch-bar, the anvil being depressed by a coiled spring, enveloping its shank, in manner as will be understood by intelligent mechanics, such spring retaining the anvil in its lowest position while the punches are being raised through it.

The device for expelling the perfected shoe from the machine consists of a long, flat bar, supported and sliding partially upon the upper surface of the bevelled gear which drives the punch-bar, and partially upon a portion of the bed of the machine, such bar being slotted, and straddling the shaft of the gear, and being driven by a cam affixed to such shaft, and by a forked pallet, pivoted to a contiguous part of the frame of the machine, in manner to be described.

The device for feeding the nail-plate to the machine consists of a spring-clamp or plate, sliding upon a lateral extension or bracket, making part of the frame of the machine, and disposed at right angles to the longest axis of such frame, the reciprocating horizontal movements of the clamp-carrier, toward and away from the die-block, being effected by two horizontal levers, pivoted, at their forward ends, to said carrier, and at their rear ends to one side of the extreme rearward of the machine-frame, while the other is pivoted, in like manner, at its front end, to the carrier, but fulcrumed at an intermediate point of the machine-frame, the two levers being actuated by an irregular-shaped cam, disposed immediately over and fixed upon the same shaft with the cam which actuates the shoe-expeller, before mentioned, the disposition of these latter levers, and their operation, being hereinafter referred to.

The device for cutting the nail-bar into proper lengths will be duly explained.

In the drawings, hereinbefore alluded to as accompanying this specification, and illustrating my invention, the main frame of the machine is denoted by the letter A, and, as the reader will see by referring thereto, is similar in its general form to the well-known Singer sewing-machine, although of much greater proportions; that is to say, it is composed of a base or bed-plate, B, two standards or supports, C C', and a gooseneck, D, the latter making part of the rear standard C', and provided with a head, E, disposed immediately over the forward standard C.

A driving-shaft, F, is supported by and revolves within a horizontal bearing, a, made in the rear standard C, and at about the centre thereof, a bevelled pinion, G, being affixed to the forward end of such shaft, and immediately in front of the standard.

Two twin-shaped wings, H H', are hinged, as shown at I, to opposite sides of the standard C of the machine, and so as to be capable of free swinging movements laterally thereon, such movements of the wings being effected by two horizontal toggle-joints, J J', of equal lengths, pivoted, at their rear extremities, to opposite sides of the extreme rear part of the standard C, and at their front ends, to the outside of the wings, the pitman of such toggle joint being shown at K and L respectively, the former, K, being pivoted to the upper surface of a horizontal bevelled gear, M, supported upon a vertical shaft, N, which extends upward from the bed of the machine, and midway, or thereabout, between the standards C C', while the latter, L, is pivoted to the under surface of the bevelled gear O, of equal capacity with the former, such gear O being fixed to the lower extremity of a vertical shaft, P, suspended from the gooseneck of the machine, and in alignment with the shaft N, the two gears M and O meshing into, and being driven by the pinion G, before mentioned.

The matrix-plates or formers, before mentioned, for bending the shoe, are shown at Q Q', as applied to the top of the wings H H' respectively, they being duplicates of each other in size and shape, and with a curved

inner boundary, which forms, when the two are together, the outline of the shoe.

R, in the drawings, denotes a bar or carrier, sliding within boxes or bearings, S T, affixed to the front face of the head E of the gooseneck D, the lower end of such bar carrying a series of punches, b b, &c., arranged in such manner as to imprint or punch the proper holes in the shoe, a small spur, c, being formed upon the lower end of the bar, and between its two central punches, for pressing upon the toe of the shoe, and holding it securely in position during the punching of it, and of bending its calks.

The lower face of the said punch-bar or carrier, as well as the upper face of the mould-block, to be described, should be of such shape as to mould the metal of the shoe into the desired form or angle.

The punches, which are or should be hollow, for containing water, in order to maintain them in a cool state, extend loosely through a horizontal plate, U, which I term a combined anvil and presser or clamp-bar, such anvil having a long shank, d, extending upward into a corresponding hole, e, made in the punch-carrier, a spiral spring, f, being applied to the shank, and within the hole, for the purpose of depressing the anvil.

The front edge of the anvil is formed with a spur, or extension, as shown at g', and its purposes are two-fold, one being to serve as an abutment for bending the heels of the shoe, and the other to remove the shoe from the punches, to which it would otherwise cling, a small spur, c, being affixed to the under side of the anvil, and its rear central part, in order to press upon the shoe-blank, when such anvil is lowered, and hold the shoe tightly in place while being bent.

The reciprocating vertical movements of the punch-carrier are effected by two levers V V', of equal size, these levers being supported upon fulcra g g', fixed to opposite sides of the rear part of the standard C' of the machine-frame, the forward and shorter arms, h h', of such levers being pivoted to opposite sides of the punch-carrier, and about equidistant from its two ends, as shown at i i', in the drawings.

The rear and longer arms j j', of the levers V V', are pivoted to two upright toggles, W W', disposed alongside opposite sides of the standard C', of the frame, the lower extremities of such toggles being hinged to the bed-plate of the machine, as shown at k k'.

A horizontal-sliding forked bar, or yoke X, is applied to the machine-frame as to straddle the rear standard C' thereof, as well as the pendent shaft N, which serves to guide its movements, the rear extremities of the arms of the yoke being pivoted to the central hinges l l' of the toggles W W', before mentioned, while the forward end of the yoke is provided with two anti-friction rollers, m m', the upper one, m, of which rolls in contact with a plate or base, n, depending from the gooseneck of the machine.

The lower roller, m', acts in conjunction with an irregular-shaped or pointed cam, o, (shown at Figure 11 of the drawing,) fixed to the shaft N, and revolving with it, the longest axis of such cam serving, as it revolves, by impinging against the roller m', to force the yoke forward, and by so doing, straightening the toggles W W', the effect of which is to elevate the rear and depress the forward arms of the levers V V', and, as a consequence, depress the punch-carrier and its punches.

A second sliding bar, Y, is disposed within a groove, Z, made in the face of the punch-carrier It before alluded to, and so as to be capable of free reciprocal sliding movements therein, the lower end of this bar being furcated, or divided into two prongs, p p', such prongs extending through the lower part of the punch-carrier, and embracing, when in their lowest positions, a portion of the opposite sides of the extension g' of the anvil before mentioned.

The lower portions of the prongs p , p' are tapering upon their front faces, in order to give a tapering form to the calks of the shoe.

The movements of the bar Y are effected by the levers V , V' before mentioned, which are pivoted to opposite ends of a cross-bar, q , secured to the front face of such bar, and in front of the punch-carrier R , the faces of the bar Y and carrier R being flush with each other.

It will be seen, by referring to the accompanying drawings, that as the fulcra of the bar Y are in advance of those of the carrier R , a longer movement of the said bar Y is effected, or sufficient to cause the prongs p , p' to descend to the proper distance to taper or sharpen the calks upon the heels of the shoe.

By making the levers V , V' perform both offices, complexity of parts is avoided.

The mould-die or block of the machine, about which the shoe is bent or formed, is shown at r in the drawings as affixed to or making part of an upright post, s , sliding within a recess, t , made in the standard C' of the machine-frame, as represented, the said mould-block being disposed immediately below the anvil U , and so that its forward part u , which corresponds in size and shape to the extension g^4 of such anvil, shall be in juxtaposition thereto, it being understood that the upper surface of the mould-block and that of the formers are upon a level when the "former" is at its greatest altitude.

The form of the mould-block in horizontal section is that which is to be imparted to the interior of the shoe, and its movements are effected by a lever, r , pivoted at its front end to the lower end of the mould-block standard s , such lever being fulcrumed to one side of the bed-plate of the machine, and under the hinge of the formers H , H' , as shown at w , while the rear extremity of such lever extends into an irregular or cam-groove, x , made in or upon the lower side of a disk, y , secured to the under side of the bevelled gear M before mentioned, and revolving with such gear, an under-side view of this disk being shown in Figure 10 of the drawings.

The device for bending the calks upon the heels of the shoe consists of a bar or slider, a^1 , disposed within bearings b^1 , b , made within or upon the standard c of the machine-frame, such slider being disposed in advance and alongside of the standard s of the mould-block, and being grooved or notched at its upper part, to straddle or partially surround a portion of such mould-block, as shown in Figure 13 of the accompanying drawings, which is a representation of the calking-bar, the anvil, and the formers H , H' .

The vertical movements of the calking-bar a^1 are actuated by a lever, c^1 , disposed alongside and outside of the lever v , and upon the same fulcrum, the forward end of each lever being pivoted to the lower end of the said calking-bar, while its rear end extends into an irregular groove, d^1 , made in the hub of the disk y , the rear arms of the two levers v and c^1 being of equal, or substantially equal length.

The comparative length and disposition of the two grooves x and d^1 are such, that the rear arms of the levers v and c^1 reach their greatest altitude at the same time, or thereabout, while the inner one, or that one actuating the forming-block, descends first and describes a much shorter movement than the lever c^1 , and in order to give the latter time to complete this longer movement, the groove d^1 is horizontal for a portion, e^1 , of its distance, as shown in Figure 9 of the drawings, which is a representation of such groove, developed upon a plane surface.

The object in giving a greater length of movement of the lever c^1 , is to force the calking-bar or tool a^1 a sufficient distance above the upper surface of the mould-block to insure the bonding of the heels of the

shoe into calks, which it accomplishes by bending such heels upward against opposite sides of the extension g^4 of the anvil, it being observed, by referring to fig. 13 of the drawings, that spaces are left between the said calking-bar and the anvil for reception of the heels of the shoe as they are bent upward.

The portion of the machine for feeding the bar of iron, from which the shoes are made, consists of a carriage, g^1 , provided with a dovetailed groove, k , and supported by means of such groove in an upright position upon a branch or bracket, t' , and upon which it freely slides, the front sides of the carriage g^1 being provided with a presser-bar or clamp, j , so applied thereto, by means of pendulous arms k , k' , and in connection with a spring, l , as shown in the drawings, as to tightly clamp and carry with it the shoe-blank or strip as it approaches the mould-block, and to loose its hold and slide over without moving the shoe-blank, in a retrograde movement, preparatory to taking a fresh hold of such blank; an adjustable stop or gauge, m , being applied to a suitable portion of the machine-frame, and in rear of the mould-block, against which the end of the blank abuts, the disposition of the stop m determining the length of the strip cut from the blank, and consequently the size of the shoe.

The necessary reciprocating movements of the carriage g^1 are effected as follows:

A short, horizontal tripping-lever, c' , is fulcrumed as shown at p' , to the top of a small bracket or shelf, q' , making part of the frame of the machine, such shelf being disposed about on a level with, or slightly above the upper surface of the bevelled gear o , before alluded to, or in such manner that the tripping-lever c' shall be in a horizontal plane with, and so as to be actuated by the cam o before mentioned, the forward and long arm r' , of such lever c' , being pivoted to the inner end of the sliding carriage g^1 .

Furthermore, a second and longer tripping-lever, s' , is pivoted at its rear end to the extreme rear end of the machine-frame, as shown at t in the accompanying drawings, while the front end of such bar s' is pivoted to the forward end of the gauge g^1 , in immediate proximity to the pivots of the lever c' , and is provided with a roller, t' , applied to it about midway between its pivot t and the lever c' , the said lever or bar s' being applied to the machine in such manner that its roller, t' , and the said lever c' , shall be in the same plane.

The lever c' , for effecting the advance, and the lever s' , for effecting the retreat of the carriage g^1 , are both actuated by the cam o , which, during its revolution, strikes first the lever c' , and next the lever s' , as will be apparent to mechanics, by whom the organization of the machine will be understood.

The shoe-blank, or piece of iron from which the shoes are made, passes through an orifice, u , made in an arm, v , making part of the forward standard O of the machine-frame, such orifice being situated directly over the benders Q , Q' before mentioned, and in the path of movement of the blank-carrier g^1 .

The lower part of the sliding punch-carrier R moves directly against, and in close contact with the inner face of the arm v , and alternately opens and closes the orifice u , and, as a consequence, cuts a portion from off the shoe-blank at every movement, it being understood that the arrangement of the parts of the machine is such, that the wings or formers H , H' remain open to their fullest extent until the punch-carrier has effected a portion of its descent, and cut from the shoe-blank the desired portion for forming the shoe.

The device or portion of the mechanism for expelling the shoe from the machine, is composed as follows:

A long, flat bar or "tappet," w , rests upon the upper surface of the gear O , and straddling its supporting

shaft, the rear end of this "tappet" sliding within a bearing, x' , made in the rear standard C' , of the machine-frame, the tappet being of such a length that its forward extremity, when at the extreme of its outward movement, shall extend to about the centre, and so as to rest upon the top of the mould-block r .

When at its extreme inward or rearward position, the end of the tappet should be somewhat in rear of the mould-block, or so as to leave abundant space for reception between the two of the shoe-blank.

The necessary reciprocating rectilinear movements of the tappet w' toward and away from the mould-block are effected as follows:

A horizontal furcated tripping-lever or pallet, y' , rests partially upon, and is fulcrumed, as shown at Z' , to the top of the bracket or shelf q' , before mentioned as supporting the lever o' for operating the feeding-mechanism of the shoe-blank or strip, the arms a^2 a^3 of such lever moving over the upper surface of the "tappet" w' , as shown in the accompanying drawings.

The longer arm, a^2 , of the pallet y' , extends laterally across the "tappet" w' , and between two studs or anti-friction rollers, b^2 b^3 , applied or affixed to the upper surface of such "tappet," the rear arm a^3 of the said pallet y' being bent at a curved angle somewhat to the rear of the roller b^3 , the latter, as a consequence, being enclosed between the two arms.

An irregular-shaped or pointed cam or wiper, c' , is affixed to and revolves with the shaft P , and is disengaged between the cam c' and the bevelled gear O , and upon a level with the pallet y' , which it actuates.

The wiper c' is so applied to the machine, that immediately after the punch-carrier and its punches have been raised, the mould-block and calking-bar completed their descent, and the feeding-mechanism and the shoe-blank advanced, the said cam shall strike the roller b^3 , and advance the tappet w' with a sudden snap, and expel the perfected shoe from the machine, it being evident to the reader, from inspection of the drawings, that the shoe-blank or strip extends over or above the upper face of the tappet, and so as not to interfere with its movements.

As the actuating-point d^2 of the wiper c' , (shown in Figure 12 of the drawings, which is a face representation of such wiper,) passes by the roller b^3 , after advancing the expelling-tappet w' , it strikes the curved rear arm a^3 of the pallet y' , and causes such pallet to describe a partial revolution upon its fulcrum, which effects a rearward movement of its arm a^2 , and, as a consequence, a retraction of the tappet w' , which thus remains at its extreme rearward position until the wiper has completed a revolution upon its axis, and again strikes the roller b^3 , and effects an advance of the tappet.

The above description embraces the construction and organization of my improved machine, and will enable skilled or intelligent mechanics, to whom this specification is chiefly addressed, to build it.

The operation of the above-described machine is as follows, it being premised with the remark that the iron strip, of which the shoes are formed, is to be suitably creased for forming the groove about the nail-holes, and maintained at a red heat while it is fed to the machine, the position of the different parts of the machine being as shown in Figure 14 of the accompanying drawings, that is, with the feeding-carriage retracted to its furthest extent, the formers or wings H H' wide open, the perch-carrier elevated, and the mould-block and calking-bar also elevated; it being remarked that the nail-plate has been inserted in place between the clamp-bar j' , and the feeding-carriage g' , and pushed inward until it strikes against the stop or gauge m' , before mentioned, and that the punch-carrier has first made one descent, and cut a piece from off such strip, of a length sufficient to form a shoe, such piece lying

upon the top of the standard C of the machine-frame, below the anvil U , and in rear of the mould-block r , or between it and the expeller or tappet w' .

Upon revolution of the driving-shaft F , as indicated by its arrow, its bevelled pinion G revolves the bevelled gears M and O in the direction of their arrow, expands the toggles J J' , and first closes the wings H H' and the formers O Q' , this closing of the "formers" around the mould bending the shoe into shape as it is enclosed between them.

While the toggles J J' are being straightened, and the wings H H' closed, the portion f^2 , of the wiper e , (see fig. 11 of the drawings,) simultaneously with the start of the wings, by striking against the roller m' , and advancing the bar, serves partially to straighten the toggles W W' , and to depress the forward arms k k' of the levers V V' , and lower the punch-bar or carrier R , and the clamp-plate or "anvil" U , until the latter, or its stud c , presses upon the shoe, and clamps it to the mould-block r , and holds it firmly in position during the closing of the wings, which is effected by the entire straightening of the toggles W W' .

As soon as the toggles W W' have become straightened, and the wings H H' closed upon and bent the shoe, the concentric portion g^2 of the wiper e revolves past the roller m' , without actuating it, while the continued revolution of the driving-shaft, by means of the irregular or cam-groove in the disk y , so actuates the lever c^2 as to elevate the calking-bar a^1 , and bend the heels of the shoe upward against the outer edge of the anvil, and upon opposite sides of its stud or projection, before mentioned, thus forming the calks upon the shoe-heels.

By the time the calking-bar a^1 has reached its highest position, the longest point e^2 of the wiper e strikes the roller m' , and completes the forward movement of the yoke X , and the straightening of the toggles W W' .

This straightening of the toggles W W' completes the descent of the punch-carrier R , and the sliding bar Y , carrying the prongs p p' , the punches having the effect of wholly or partially punching the nail-holes in the shoe, and the prongs having the effect of tapering the calks formed by the calking-bar a^1 , it being borne in mind that the lower end of the punch-carrier, or that enclosed within the radius of rows of punches, as well as the upper surface of the mould-block, are of such configuration as to give the necessary shape or curve to the faces of the shoe.

The descent of the punch-carrier, as it passes by the orifice u' , before mentioned, has the effect of severing the shoe-strip at this point, preparatory to a renewed revolution of the driving-shaft of the machine.

It should also be borne in mind at this point, that as the anvil or clamp U is resting upon the mould-block during the last part of the descent of the punch-carrier, a yielding connection between such clamp and carrier becomes necessary.

The shank and spring, before mentioned, provide for this necessity.

It will also be well to call the reader's attention, at this point, to the fact that the lower part of the punch-carrier, and preferably that of the punches themselves, should be hollow, and should contain water for reducing the temperature of these parts, as well as that of the completed shoe, which otherwise would injure or incapacitate them, and cause a cessation of working of the machine.

As soon as the point e^2 of the wiper e passes by the roller m' , the toggles are suddenly contracted by a suitable cam, spring, or other device, and the punch-carrier and sliding bar Y are suddenly elevated.

After passing the roller m' , the point e^2 of the wiper e comes in contact with the shorter arm of the tripper y , and partially turns such tripper on its fulcrum, by

this means advancing its longer arm, and with it the feeding-carriage, which, in turn, carries with it the shoe-strip, and inserts such strip anew to the action of the machine.

Soon after passing the tripper, the wiper o strikes the roller t' of the long lever s' , and pushing the free end of such lever outward, causes the carriage g' to slide over the shoe-strip, and take a fresh grip thereupon.

I have now shown how the nail-strip is fed into the machine, and cut to the desired length, and how it is bent into shape, and moulded and punched.

I will now explain the action of that portion of the machine for expelling the perfected shoe, and to do this, I go back to the point and time at which the wiper o is impinging against, and actuating the tripper r' and advancing the shoe-strip.

At this point, the largest portion or point of the wiper or cam c' , which is somewhat in rear of that of the wiper o , comes in contact with the roller b' , and advances the tappet w' , and expels the shoe from the machine; the anvil, punch-carrier, and calking-bar, at this time, being at their highest positions.

After passing by the roller b' , the wiper c' strikes the curved rear arm a^2 of the pallet, and retracts its arm a^2 , and with it the tappet, substantially as before explained.

It will be obvious that while the wiper o is impinging against the tripper r' and the roller t' , the toggles W W' and J J' are being contracted or shortened, and, as a consequence, the punch-carrier and calk-tapering bar elevated, and the wings H H' opened, while at the same time, by the revolution of the disk y , and the action of the levers c' and r' , the mould-block and calking-bar a^1 are depressed.

After leaving the curved arm a^2 of the pallet y , the wiper c' completes its revolution without further effect, until it again comes in contact with the roller b' , and advances the tappet w' .

The machine, constructed as above described, is very compact in bulk, and may be built at moderate cost.

It is very powerful and effective in operation, and its elements or mechanical movements are all positive motions.

What I claim as my invention, and desire to secure by Letters Patent of the United States of America, is as follows:

1. The train of mechanism by which the formers Q Q' are opened and closed, its several parts being constructed, arranged, and operating substantially in the manner described.
2. Constructing, arranging, and fitting together, upon the head-block, the sliding bars R Y and levers V V' , substantially in the manner specified.
3. The train of mechanism by which the sliding bars R Y are actuated, its several parts being arranged and operated as set forth.
4. The combination of the anvil-plate, the pressure-plate u , and bar r , acting together as a holding-device, with the dies a^1 and y , all being constructed and arranged as shown and described.
5. The subject-matter of the preceding clause, in combination with the formers Q Q' , all the elements of said combination being arranged and operating together as and for the purpose specified.
6. The subject-matter of the preceding clause, in combination with the punches p p' , all the elements operating together to make a complete shoe, as set forth.
7. The combination of the bending, punching, face-forming, ealk-forming, and discharging devices, all arranged and operating together, as and for the purpose specified.
8. The arrangement of the punch-carrier R , the orifice H' , the feeding-carriage g' , and the herein-described mechanism for reciprocating the same, substantially as and for the purposes set forth.

A. J. ROBERTS.
